US0D1059973S

(12) **United States Design Patent** (10) **Patent No.:** **US D1,059,973 S**
(45) **Date of Patent:** **** Feb. 4, 2025**

(54) **BEVERAGE DISPENSER**

(71) Applicant: **Neil Aneja**, Roanoke, VA (US)

(72) Inventor: **Neil Aneja**, Roanoke, VA (US)

(**) Term: **15 Years**

(21) Appl. No.: **29/814,644**

(22) Filed: **Nov. 8, 2021**

(51) **LOC (15) Cl.** **07-99**

(52) **U.S. Cl.**

USPC **D7/700**

(58) **Field of Classification Search**

(57) **CLAIM**

The ornamental design for a beverage dispenser as shown and described.

DESCRIPTION

FIG. 1 is a top, right side perspective view of a beverage dispenser;

FIG. 2 is a right side view of the beverage dispenser;

FIG. 3 is a bottom, right side perspective view of the beverage dispenser;

FIG. 4 is a top view of the beverage dispenser; and,

FIG. 5 is a bottom view of the beverage dispenser.

A left side view of the beverage dispenser is a mirror image of the right side view shown in FIG. 2.

The broken lines depict portions of the beverage dispenser that form no part of the claimed design.

1 Claim, 3 Drawing Sheets
